UNITED STATES PATENT OFFICE.

WILLIAM MARTIN, OF NEW YORK, N. Y.

MACHINE FOR EDGING METALLIC ROOFING-PLATES.

SPECIFICATION forming part of Letters Patent No. 655,904, dated August 14, 1900.

Application filed November 7, 1899. Serial No. 736,108. (No model.)

To all whom it may concern:

Be it known that I, WILLIAM MARTIN, a citizen of the United States, and a resident of the borough of Manhattan, in the city and 5 State of New York, have invented a new and useful Machine for Edging Metallic Roofing-Plates, of which the following is a specification.

My invention relates to a machine for "edging" metallic roofing-plates, with the object 10 in view of providing a hand-machine, as distinguished from a power-machine, which shall be efficient and inexpensive and which shall be capable of materially reducing the time 15 and labor of the edging operation.

In the accompanying drawings, Figure 1 is a view of the machine in side elevation. Fig. 2 is a partial front elevation. Fig. 3 is a top plan view. Fig. 4 is a view in detail showing 20 the position of the bending-tool as it completes its operation. Fig. 5 represents a sheet half-edged. Fig. 6 is an edge view of the same, and Fig. 7 is a view of a sheet completely 25 edged.

The present machine is designed to simultaneously turn the two adjacent edges of a sheet by a single depression of the foot, the operator then turning and reversing the plate for turning the remaining two edges of the 30 sheet in the opposite direction by a second depression of the foot.

A represents the supporting-frame, which may be of any approved form suitable to the purposes in hand. It is here shown as composed of skeleton sides connected by guides and having a general rectangular shape in horizontal section.

A flat table B is provided at the top of the frame A for holding the sheet S to be edged 40 while the edging-tools are operating on it. The table B is provided with straight edges b b', adjacent to and extending at right angles to each other, and so located with respect to the edging-tools as to serve as anvils over which 45 the edges of the sheet S are bent. The bending-tools are quite similar in structure, and hence a particular description of one will suffice for both.

A hub or sleeve C is mounted on a spindle 50 D, supported in the upper ends of a pair of flexible standards E. The lower ends of the standards E are fixed to the supporting-frame

A, and their upper ends are free to move bodily toward and away from the edge of the sheet. The hub or sleeve C is provided with 55 a bending lip or flange c, extending the length of the edge to be bent and with a tailpiece c', to which the operating-rod F is attached for rocking the hub or sleeve to effect the bending of the edge of the sheet. The hub or 60 sleeve C is further provided with an arm c², carrying an antifriction-roller in its end in position to engage the tailpiece g of the rocking clamp G for pressing the plate firmly on the table B while the bending operation takes 65 place. The clamp g is attached to a rocking spindle g', mounted in the overhanging arms h h' of a bracket H, secured to the supporting-frame, and a coiled spring g², having one end attached to the spindle and the 70 other to one of the arms h or h', serves to retract the clamp out of engagement with the sheet when the bending is completed. The bracket H also has thereon a cam extension h² in position to engage the end of the tailpiece c' as the latter is forced upwardly by 75 the rod F to move the bending-tool bodily toward the edge of the sheet to complete the bending of its edge. The edge of the clamp G, which is forced into engagement with the sheet, is preferably provided with some tough 80 yielding material g³—such, for example, as rubber or leather—to prevent chafing the sheet and to adapt the clamp to sheets of slightly-varying thicknesses. A similar bending-tool and clamp are located on the adjacent 85 side of the machine to that occupied by the parts just described, and its operating-rod F' is connected with the foot-lever K through an intervening horizontal lever L and rod F², 90 leading from the lever L to the foot-lever intermediate of its fulcrum k and its treadle k', while the operating-rod F extends directly to the foot-lever K on the opposite side of its fulcrum. By means of these connections a 95 downward movement of the pedal lifts the tailpieces on both the bending-tools and simultaneously brings the tools into engagement with the two adjacent edges of the sheet, bending the edges downwardly and inwardly. This having been accomplished, the operator may turn the sheet half-way around edgewise and reverse it and again bring the 100 tools into engagement with the remaining

edges to turn them in a direction opposite that in which the edges were first turned, and the sheet is then ready for use on the roof.

It is obvious that changes might be resorted 5 to in the form and arrangement of the several parts without departing from the spirit and scope of my invention. Hence I do not wish to limit myself strictly to the structure shown and described; but

10 What I claim is—

15 1. The combination with means for supporting the sheet in position to be operated upon, of a bending-tool mounted to rock and movable bodily toward and away from the edge of the sheet, the said bending-tool being provided with a lip or flange in position to engage the edge of the sheet, means for rocking the tool, and means for moving the tool bodily toward and away from the edge of the sheet 20 during its rocking movement, substantially as set forth.

25 2. The combination with means for holding the sheet in position, of a flexible support, a rocking tool mounted in the flexible support and means for rocking the tool and forcing

the flexible support and tool thereon toward the edge of the sheet of metal, substantially as set forth.

3. The combination with a support for the sheet to be operated upon and a sheet-holder, 30 of a rocking tool for engaging the edge of the sheet, means in connection with the rocking tool for operating the sheet-holder and means for operating the tool and hence the sheet-holder, substantially as set forth.

35 4. The combination with a sheet-support and a spring-actuated sheet-holder mounted over the edge of the sheet, of a rocking tool for engaging the edge of the sheet, an arm on the rocking tool for operating the spring-actuated sheet-holder and means for rocking the tool, substantially as set forth.

40 In testimony that I claim the foregoing as my invention I have signed my name, in presence of two witnesses, this 28th day of October, 1899.

45 WILLIAM MARTIN.
